CLAIM

The ornamental design for a mobile phone, as shown and
described.

DESCRIPTION

1. Mobile phone

1.1 : Perspective

1.2 : Front

1.3 : Back

1.4 : Left

1.5 : Right

1.6 : Top

1.7 : Bottom

1.8 : Back perspective

The broken lines depict portions of the mobile phone that
form no part of the claimed design; reproduction 1.1 is a
front perspective view of the mobile phone; reproduction 1.2
is a front view thereof; reproduction 1.3 is a back view
thereof; reproduction 1.4 is a left view thereof; reproduction
1.5 is a right view thereof; reproduction 1.6 is a top view
thereof; reproduction 1.7 is a bottom view thereof; repro-
duction 1.8 is a back perspective view thereof.

1 Claim, 8 Drawing Sheets
